CLAIM

The ornamental design for a baby changing bag, as shown and described.

DESCRIPTION

FIG. 1 is a front right perspective view of a reconfigurable baby changing bag with both the shoulder strap and backpack straps attached, showing the new design;

FIG. 2 is a front right perspective view thereof, in a shoulder bag configuration;

FIG. 3 is a front right perspective view thereof, with the shoulder strap shown extended;

FIG. 4 is a front right perspective view thereof; in a backpack configuration; and,

FIG. 5 is a front view thereof.
